COMBINATION CONTAINER FOR A PILL AND WATER

Florabel Maben, 3632 Park Blvd., Apt. E,
Visalia, Calif. 92103

Filed Mar. 26, 1969, Ser. No. 16,451

Term of patent 14 years

Int. Cl. D9—01

U.S. Cl. D9—169

FIGURE 1 is an elevational view of a combination container for a pill and water embodying my new design, the side opposite that shown being substantially the same in appearance as the side shown;

I claim:

The ornamental design for a combination container for a pill and water, as shown and described.
